INTERMITTENT DISCHARGE INDUCTION
MELTING FURNACEPaul E. Petersen, Waterbury, Conn., assignor to
Chase Brass & Copper Co. Incorporated, Water-
bury, Conn., a corporation

Application December 28, 1945, Serial No. 637,515

3 Claims. (Cl. 13—29)

1

The present invention relates to improvements in melting-furnaces and relates more particularly to melting-furnaces of the intermittent discharge type, i. e., melting-furnaces designed to discharge a portion of their contents of molten metal or the like at relatively-short intervals, rather than discharging their contents substantially completely at one time.

One of the main objects of the present invention is to provide a superior intermittent discharge melting-furnace characterized by simplicity and reliability of operation.

Another object of the present invention is to provide a superior induction-heated melting-furnace which may be discharged without requiring the shutting-off of the current-supply thereto and therefore without requiring the cessation of melting during such discharge.

A further object of the present invention is to provide a superior melting-furnace of the character referred to, which may be either intermittently or continuously supplied with unmelted metal or the like which, after being melted, may be effectively intermittently discharged.

Still another object of the present invention is to provide a superior intermittent discharge melting-furnace especially well suited for the melting of relatively-small particles of material such, for instance, as brass chips, small-arms cartridge-cases, etc.

A still further object of the present invention is to provide a superior melting-furnace of the character referred to, which is capable of melting material in the presence of an inert or reducing atmosphere.

With the above and other objects in view, as will appear to those skilled in the art from the present disclosure, this invention includes all features in the said disclosure which are novel over the prior art.

In the accompanying drawings, in which certain modes of carrying out the present invention are shown for illustrative purposes:

Fig. 1 is a top or plan view of an intermittent discharge melting-furnace embodying the present invention;

Fig. 2 is a transverse sectional view taken on the line 2—2 of Fig. 3 but with the pool of molten metal omitted;

Fig. 3 is a vertical central section taken on the line 3—3 of Fig. 1, and

Fig. 4 is a transverse sectional view taken on the line 4—4 of Fig. 3 but on a larger scale.

The particular intermittent discharge melting-

2

furnace illustrated in the accompanying drawings for purposes of making clear one form of the present invention, is of the induction-type and includes a casing generally designated by 5 the reference character 10 and comprising a multi-part shell 11 and a multi-part lining 12.

The shell 11 above referred to may conveniently be formed of cast iron or the like, while the relatively-thick lining 12 is preferably formed 10 of ceramic material resistant to the eroding and other harmful effects of a pool of molten metal or the like 13 adapted to be contained within the casing 10.

The casing 10 is so shaped as to provide with- 15 in its interior what might be aptly termed a "melting-compartment" or portion 14 located to the right as viewed in the drawings, and a "storage-compartment" or portion 15 located to the left, all as is especially well shown in Figs. 20 2 and 3.

Leading downwardly from the lower portion 25 of the melting-compartment 14 proper, is a substantially U-shaped passage 16 into which the molten metal extends, to provide what is com- monly known in the art of induction furnaces as a "loop" which acts as a "secondary" for a primary winding 17 extending through the aforesaid loop. In the instance shown, the primary winding 17 encircles the upper reach of 30 the usual magnetic core designated by the reference character 18.

Communicating with the lower portion of the storage-compartment 15 proper, is a U-shaped 35 passage 19 similar to the U-shaped passage 16 before referred to, and serving to accommodate molten metal in the form of a so-called "loop" or "secondary" for a primary winding 20. The primary winding 20 encircles the upper reach 40 of a magnetic core 21 similar to the magnetic core 18 before referred to.

Connected to the top wall of the casing 10 at a point preferably centrally with respect to the melting-compartment 14, is a charging-tube 22 communicating at its lower end with an out- 45 wardly-and-downwardly-flared charging-opening 23 formed in the upper portion of the lining 12 of the casing 10, as is especially well shown in Fig. 3.

Extending through the side wall of the lining 50 12 and the shell 11, is a gas-inlet passage 24 located above the level of the pool of molten metal 13. The inner-end of the passage 24 communicates with the upper portion of the melting-compartment 14, though when desired it may 55 communicate directly with the storage-com-

partment 15. At its outer end the passage 24 communicates with a supply-pipe 25 leading from any suitable source of an inert or reducing-gas, all for purposes as will more fully hereinafter appear.

Preferably and as shown, there is interposed between the melting-compartment 14 and the storage-compartment 15 what might be aptly termed a "baffle-wall" designated by the reference character 26. The said baffle-wall may be formed integrally with the remainder of the lining 12 if desired and, as shown, terminates short of the top of the lining to provide a gas-passage 27 through which a reducing-gas or an inert gas may flow into the storage-compartment 15.

The baffle-wall 26 above referred to also terminates short of the bottom of the main portion of both the melting-compartment 14 and the storage-compartment 15 to provide a flow-passage 28 through which molten metal may flow between the two said compartments.

The side wall of the casing 10, at a point opposite the melting-compartment 14, is provided with an inverted U-shaped discharge-passage 29 communicating at its inner-end with the lower portion of the pool of molten metal 13 below the upper surface thereof and having an outer leg or reach located exteriorly of the main portion of the casing 10, so as to discharge molten metal into any suitable receptacle such as a mold.

The material of the lining 12 is so shaped adjacent the cross-reach of the inverted U-shaped discharge-passage 29 as to provide what may be aptly termed an "overflow-lip" 30 located above the normal level of the pool of molten metal 13 within the casing 10, and over which molten metal from the storage-compartment 15 is adapted to be flowed on occasion, all in a manner as will more fully hereinafter appear.

For the purpose of causing the pool of molten metal 13 to flow over the overflow-lip 30 without requiring the tilting of the furnace, a relatively-thick disk-like metal-displacing member 31 is employed. The said metal-displacing member may be formed of any suitable material resistant to the effects of molten brass and the like, such, for instance, as carbon or ceramic material.

The metal-displacing member is located within the storage-compartment 15 and is normally retracted upwardly substantially out of the pool of molten metal 13 as is shown by full lines in Fig. 3, though movable downwardly in the said pool, as is indicated by the broken lines in Fig. 3.

The metal-displacing member 31 above referred to is coupled to the respective lower ends of three (more or less) parallel synchronized plungers 32 which are adapted to reciprocate through the top wall of the casing 10 and which project above the said top wall to a considerable extent for purposes as will hereinafter appear.

Each of the three plungers 32 corresponds to the other and has its upper portion threaded as at 33, as is indicated in Fig. 3, and extended upwardly through a housing 34.

The housing above referred to is held in spaced relationship above the top surface of the casing 10 by means of a standard 35 and accommodates three plunger-actuating gears 36, as is indicated in Figs. 3 and 4. The gears 36 are arranged equidistantly around and in mesh with a drive-gear 37 mounted for rotation centrally within the housing 34 and operatively connected to a drive-motor 38 mounted upon the top of the housing 34 and preferably of the reversible type.

As is indicated in the upper portion of Fig. 3,

the threaded upper portion 33 of each of the given plungers 32 is in threaded engagement with the threaded bore of its complemental one of the plunger-actuating gears 36, so that as the latter is turned in one direction or the other, it will either lower or raise the given plunger 32 in synchronism with the similar movement of the other plungers.

Operation

10 Let it be assumed that both of the primary windings 17 and 20, having terminals 170 and 200 respectively, are energized and pieces of metal are being continuously introduced into the melting-compartment 14 through the charging-tube 22 and the charging-opening 23, so as to become immersed in the pool of molten metal 13 for being rapidly melted therein.

It may further be assumed that an inert or reducing-gas is being continuously introduced 20 under pressure into the interior of the casing 10 through the supply-pipe 25 and gas-inlet passage 24. It may here be noted that when a reducing-gas is employed, provision will be made to prevent the unhindered escape thereof through 25 the upper end of the charging-tube 22.

Now when it is desired to discharge a portion 30 of the pool of molten metal 13, the electric drive-motor 38 will be energized to cause the three plungers 32 to descend in synchronized relationship, to thereby force the metal-displacing member 31 downwardly into the pool 13, as is indicated by the broken lines in Fig. 3.

The descent of the metal-displacing member 31 will cause the level of the pool 13 to rise sufficiently to cause molten metal to flow over the overflow-lip 30 and into a mold or any suitable receptacle located beneath the outer end of the discharge-passage 29. The rapidity of the downward movement of the metal-displacing member 40 31 will, of course, determine the rapidity of the outflow of molten metal through the discharge-passage 29 and may be precisely controlled.

As soon as sufficient metal has flowed over the 45 overflow-lip 30 to fill the desired receptacle, the metal-displacing member 31 may be raised by suitably energizing the drive-motor 38, to thereby lower the level of the pool of molten metal 13 and effectively shut off the further flow of the metal until such time as such flow is again desired.

Instead of continuously supplying unmelted 55 metal into the furnace, such metal may be intermittently introduced thereto, either in the form of so-called "chips," in the form of massive pieces of metal, or mixtures thereof.

From the foregoing it will be seen that by means of the present invention, the intermittent discharge may be effected without tilting the furnace and without losing the desired inert or reducing atmosphere within the furnace. Such controlled amount of inert or reducing atmosphere as may be desired can be permitted to move upwardly through the charging-tube 22 without reducing the required gas-pressure within the 60 furnace.

Furthermore and by means of the present invention, an induction melting-furnace may be discharged without requiring the cutting-off of the current thereto during the discharge period 70 with the consequent loss of melting-time. In this connection it may be explained that when ordinary induction furnaces are tilted to effect the discharge of the major portion of their contents, it is necessary to shut off the supply of current, inasmuch as to leave the current on

when the "head" of metal above the loop is materially lessened would cause the remaining metal to be so violently agitated as to be squirted indiscriminately over the interior of the furnace.

The invention may be carried out in other specific ways than those herein set forth without departing from the spirit and essential characteristics of the invention, and the present embodiments are, therefore, to be considered in all respects as illustrative and not restrictive, and all changes coming within the meaning and equivalency range of the appended claims are intended to be embraced therein.

I claim:

1. An intermittent discharge melting-furnace comprising a furnace-casing having a melting-portion and a storage-portion arranged side by side therein; individual induction heating-means mounted within said melting-portion and said storage-portion respectively; a partition separating said melting-portion and said storage-portion, said partition having a liquid-transfer passage in the bottom thereof and a gas-pressure equalizing-passage in the top thereof, each passage communicating with said melting-portion and said storage-portion; a charging-opening in the top of said melting-portion; a discharge-passage in the wall of said storage-portion comprising an overflow-lip located above the normal level of a pool of molten metal in the said storage-portion; a metal-displacing member supported entirely within said storage-portion and movable toward and away from the pool of molten metal therein; and operating-means comprising a power-driven plunger connected to said metal-displacing member arranged positively to move said metal-displacing member into the pool of molten metal in the said storage-portion to raise the level of the said pool above the overflow-lip in the discharge-passage of said storage-portion.

2. An intermittent discharge melting-furnace comprising a furnace-casing having a melting-portion and a storage-portion arranged side by side therein; a recess in the bottom of each of said melting- and storage-portions; induction heating-means in the respective recesses of said melting- and storage-portions; a partition separating said melting-portion and said storage-portion, said partition having a liquid-transfer passage in the bottom thereof and a gas-pressure equalizing-passage in the top thereof, each passage communicating with said melting-portion and said storage-portion; a charging-opening in the top of said melting-portion; a discharge-passage in the wall of said storage-portion comprising an overflow-lip located above the normal level of a pool of molten metal in the said storage-portion; a metal-displacing member supported entirely within said storage-portion and movable toward and away from the pool of molten metal therein; and metal-displacing member operating-means comprising a plurality of power-driven plungers connected to said metal-displacing member positively to move the same into the pool of molten metal in the said storage-portion to

raise the level of the said pool above the overflow-lip in the discharge-passage of said storage-portion.

3. An intermittent discharge melting-furnace including in combination: a furnace-casing having a melting-portion and a storage-portion arranged side by side therein; individual induction heating-means mounted within the said melting-portion and the said storage-portion respectively; a partition separating the said melting-portion and the said storage-portion and extending both above and below the normal level of molten metal in the melting-portion and the storage-portion, the said partition being constructed and arranged to prevent unmelted metal and dross in the said melting-portion from moving laterally across the surface of the molten metal into the said storage-portion; the said furnace-casing being provided with a liquid-transfer passage located below the normal level of molten metal in the two said portions and providing communication therebetween, the said furnace-casing also being provided above the normal level of molten metal in the said melting-portion and storage-portion with a gas-pressure equalizing-passage interconnecting the two said portions; a charging-opening leading into the said melting-portion; a discharge-passage in the wall of the said storage-portion comprising an overflow-lip located above the normal level of molten metal in the said storage-portion; a metal-displacing member located within the said storage-portion and movable toward and away from the pool of molten metal therein; and power-driven operating-means connected to the said metal-displacing member and arranged to positively move said metal-displacing member into the pool of molten metal in the said storage-portion to raise the level of the said pool above the overflow-lip in the discharge-passage of the said storage-portion.
